UNITED STATES PATENT OFFICE

WILLIS A. JENNINGS, OF CHICAGO, ILLINOIS

SOAP DISPENSER

Application filed October 26, 1929. Serial No. 402,665.

This invention appertains to soap dispensing devices of the type adapted to be placed over a washbowl or basin and one of the primary objects of my invention is to provide a novel 5 soap holder which will permit the use of the cake of soap by merely rubbing the hands over the top face of the soap held by the holder, and thereby eliminating the necessity of removing the soap from the holder and 10 the consequent waste thereof.

Another important object of my invention is the provision of a holder for a cake of soap embodying a casing slidably mounted on a standard which is adapted to be secured 15 to the wall or a bracket above the wash basin, with a novel follower plate slidably mounted in the casing and supported by the standard whereby upon adjustment of the casing on the standard, the cake of soap can be held the 20 required distance above the top of the casing for use.

A further important object of my invention is the provision of novel means for forming the follower plate so as to insure the 25 proper holding of the soap in place and to permit soap of different shapes to be used.

A further object of my invention is the provision of novel means for locking the casing in an adjusted position on the standard 30 and relative to the follower plate for the soap.

A further object of my invention is the provision of a novel soap holder embodying an inner or foundation part for supporting the soap and an outer casing or shell for housing the soap, which is retarded in its movement either by friction or other desirable locking means.

A still further object of my invention is 40 to provide a holder for a cake of soap of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which:

Figure 1 is a side elevation of one of my improved soap holders showing the same partly broken away and in section;

Figure 2 is a vertical section taken on the line 2—2 of Figure 1 looking in the direction 55 of the arrows;

Figure 3 is a top plan view of my improved soap holder;

Figure 4 is a detail perspective view of the follower plate showing the bottom thereof; 60

Figure 5 is a detail horizontal section taken on the line 5—5 of Figure 1 looking in the direction of the arrows illustrating the means employed for holding the casing in an adjusted position on the standard; 65

Figure 6 is a transverse section through the body portion of a slightly modified form of my soap holder;

Figure 7 is a detail perspective view of the follower plate in the modified form of soap 70 holder;

Figure 8 is a top plan view of a still further modified form of soap holder;

Figure 9 is a vertical section through the same taken on the line 9—9 of Figure 8 looking in the direction of the arrows; 75

Figure 10 is a detail perspective view of the follower plate employed in the form shown in Figures 8 and 9 of the drawings, the bottom of the follower plate being turned 80 upward;

Figure 11 is a view similar to Figure 9 showing a different means of arranging the spring in the device;

Figure 12 is a fragmentary vertical sectional view showing the outer casing retarded in its sliding movement by the use of leaf springs, and 85

Figure 13 is a vertical sectional view showing a still further modified form of casing in which the outer shell or casing is held in its adjusted position by frictional contact with the foundation part for the soap. 90

Fig. 14 is a vertical section of an additional modification showing the casing adjustably attached to the follower supporting post by a threaded connection. 95

Referring to the drawings in detail, where in similar reference characters designate corresponding parts throughout the several 100

views, the letter A generally indicates my improved soap holder which comprises a vertical supporting standard or post 15. The standard or post 15 is provided with a right angularly extending horizontally disposed arm 16 which can be secured to the wall above a wash basin in any desired way. In the present instance I have shown the inner end of the arm 16 provided with a clamp 17 for detachable connection with a suitable supporting bracket (not shown). The clamp 17 includes an arcuate jaw 18 formed directly on the arm 16 and a companion arcuate jaw 19 which is adjustable toward and away from the rigid jaw 18. As shown, the adjustable jaw 19 is provided with a shank 20 and a bolt 21 extends through the arm 16 and the shank 20. If desired, the shank can be provided with an inwardly extending foot 22 for engaging the arm 16 and which foot functions in the nature of a pivot or fulcrum for the jaw.

In the form of my invention shown in Figures 1 to 3 inclusive, the vertical post or standard 15 has formed thereon a stop collar 23 for a purpose which will be later described.

A casing 25 for receiving the cake of soap is slidably mounted upon the standard 15 above the collar or flange 23 and is adjustable thereon. The casing 25 is shaped to conform to the configuration of the cake of soap with which it is used and thus the casing is made in a variety of configurations. In the form shown in Figures 1 to 7 inclusive the casing is of a rectangular configuration and includes the side walls 26, the end walls 27, and a flat bottom wall 28. The upper edges of the side and end walls 26 and 27 can be bent back upon themselves to form a reinforcing bead 29 which also eliminates the formation of sharp cutting edges. The lower or bottom wall 28 has formed on its axial center the depending sleeve 30, the lower end of which can be provided with an annular guide flange 31. The post 15 is slidably received within the guide flange 31 and the sleeve 30 and extends into the casing 25. Arranged in the casing 25 is a false bottom or follower plate 32 which is shaped to conform to the configuration of the casing 25 and in the present instance this false bottom or follower plate 32 in Figures 1 to 4 inclusive is shown to embody a flat bottom wall 33 and a depending marginal flange 34. The bottom wall 33 of the follower plate is provided with an axially disposed boss 35 which is slidably received within the sleeve 30. This boss 35 is provided with a socket 36 for the reception of the upper end of the standard 15 which can be pointed, if desired.

In order to hold the casing in an adjusted position on the standard 15, the sleeve 30 can be provided with a winged set screw 37 which

can impinge against the standard 15 for locking the casing against movement thereon.

In use of this form of the device, the standard 15 is secured in place above a washbowl in the desired way and the cake of soap is placed within the casing 25 on the false bottom or follower plate 32 and the same is ready for use. The hands can be moistened and rubbed over the top face of the cake of soap and as the soap wears down the casing 25 can be lowered on the standard 15 and again locked in position by means of the set screw 37. As the casing is lowered, the follower or false bottom 32 urges the soap above the top face of the casing so that the same can again be conveniently used.

If desired, any preferred means can be employed for connecting the cake of soap to the follower plate so that the same cannot be removed from the receptacle and thus the follower plate can be provided with spurs for digging into the soap.

I can also employ an expansion spring 38 which can be placed around the post 15 intermediate the sleeve 30 and the collar or flange 23 formed on the said post and this spring normally functions to raise the casing on the post and the casing is held in an adjusted position against the tension of the spring by the set screw 37. By this arrangement, as soon as the set screw is loosened the casing will be automatically pushed upward.

In Figures 6 and 7 I have shown a slightly modified form of follower plate, which is indicated by the reference character 40, and this follower plate is arcuated transversely of a central longitudinal line so as to conform to a cake of soap which is arcuated transversely as shown in Figure 6 of the drawings. In all other respects the device is the same as the form above described.

In Figures 8 to 11 inclusive I have shown a further modified form of my invention in which the casing, which is indicated by the reference character 50, is of a cylindrical form so as to receive a circular cake of soap as indicated in Figure 9 of the drawings in dotted lines. This cylindrical casing 50 is formed relatively long so as to receive one or more cakes of soap and the bottom wall 51 thereof can be of a conical or tapering shape as shown with the sleeve 52 formed on its apex or axial center. The follower plate 53, in this form, is of a circular configuration and the bottom wall 54 thereof is of a concavo-convex shape with its convex surface disposed uppermost and the edge thereof is provided with a depending marginal flange 55. The boss 56 which receives the upper end of the standard 15 is disposed within this flange and the boss does not extend into the sleeve as shown in the previous form.

In Figure 9 I have shown the coil spring completely eliminated and the casing is moved up and down on the standard by the

hands of the operator and is locked in position by means of the set screw.

In Figure 11 of the drawings I have shown a coil spring 58 which can be housed within 5 the casing and this spring is of the expansion type and is placed around the standard 15 and is confined between the boss 56 of the follower plate or false bottom 53 and the lower wall 51 of the casing 50. In this instance the follower 10 plate 53 can be secured to the standard 15 by means of threads and the spring will function to normally draw the casing down on the standard and the casing is held in an adjusted position against the tension of the 15 spring by means of the set screw.

It is to be noted that the soap used in the form of my invention shown in Figure 9 of the drawings has its upper face convex and its lower face concave and the soap, where 20 more than one cake is used, fits one on top of the other.

In Figure 12 I have shown the set screw entirely eliminated and the lower wall 51 of the casing 50 has secured thereto inwardly directed leaf springs 60 which have their terminals bent at substantially right angles for frictional contact with the post 15, as at 61. Thus the casing is held in an adjusted position 25 relative to the standard by the leaf springs 60.

In Figure 13 I have shown a still further 30 form of my invention which may comprise an inner shell or foundation part 65 and an outer shell 75. The inner shell 65 includes a top wall 66 and depending side and end walls 67. The lower edges of the side and end walls 67 35 are preferably bent outward to provide a drip trough 68. The supporting standard, indicated by the reference character 69, is riveted or otherwise secured as at 70 to the inner face 40 of the top wall 66.

The outer shell or protecting casing for 45 the soap includes side and end walls 76 which preferably have their upper edges rolled as at 77 to eliminate the presenting 50 of sharp and cutting edges. If desired, the top edges of the end walls can carry longitudinally extending retaining wires 78 for the soap. The casing or outer shell 75 is held in an adjusted position on the inner shell 65 by the frictional contact of the side and end walls of the outer shell with the side and end walls of the inner shell.

In Figure 14, I have shown another form 55 of my invention, which is similar to Figure 9 and in this figure I have provided a post 15 with threads 80 and threaded the sleeve 52 directly thereon. Thus by turning the casing 50 the same can be adjusted up or down on the post to move the soap above 60 or below the upper edge of the casing.

From the foregoing description it can be seen that I have provided a novel soap holder in which the soap can be readily dispensed and used in an economical fashion.

Changes in details may be made without

departing from the spirit or the scope of this invention.

What I claim as new is:

1. A soap holder of the character described comprising a standard disposed in a vertical plane, a casing slidably mounted on the standard, a follower plate arranged in the casing and carried by the upper end of the standard, spring means normally urging the casing in one direction on the standard, and means for locking the casing in an adjusted position on the standard. 70

2. A soap holder of the class described comprising a standard, a casing slidably mounted on said standard, a follower plate arranged 80 in said casing and carried by the end of said standard, spring means normally urging said follower and casing apart, and means for locking the casing in an adjusted position upon the standard. 85

In testimony whereof I affix my signature.
WILLIS A. JENNINGS.
